UNITED STATES PATENT OFFICE.

LOUIS B. PRAHAR, OF BROOKLYN, NEW YORK.

DESIGN FOR THE ORNAMENTATION OF CHATELAINE-BAG FRAMES.

SPECIFICATION forming part of Design No. 19,305, dated September 10, 1889.

Application filed August 3, 1889. Serial No. 319,689. Term of patent 7 years.

To all whom it may concern:

Be it known that I, LOUIS B. PRAHAR, of Brooklyn, in the county of Kings and State of New York, have invented a new and original 5 Design for the Ornamentation of Chatelaine-Bag Frames and their Appendages, of which the following is a specification, reference being had to the accompanying drawing, forming a part thereof.

10 The leading feature of the design consists of the representation of an approximate crescent-like figure, ornamented by a series of seemingly overlapping trefoil figures.

15 The accompanying photograph illustrates a plan view of the design.

The frame and support consist of curved lines drawn to imitate crescent-like figures A and B, and between the curved lines defining

the said figures A and B a series of trefoil figures D are formed, having the appearance 20 of being connected one with the other.

In connection with the trefoil figures, rosette-like figures E are employed, each of which latter figures are seemingly mounted upon one of the trefoil figures. 25

I claim—

A design for the ornamentation of chatelaine-bag frames and their appendages, comprising an approximate crescent-like figure 30 ornamented with a series of trefoil figures representing the fragment of a wreath, as set forth.

LOUIS B. PRAHAR.
